US0D1082143S

(12) **United States Design Patent** (10) **Patent No.:** **US D1,082,143 S**
(45) **Date of Patent:** **** Jul. 1, 2025**

(54) **HAIR REMOVAL DEVICE**

(71) Applicant: **Shenzhen Ulike Smart Electronics Co., Ltd.**, Shenzhen (CN)

(72) Inventor: **Hanwen Cai**, Shenzhen (CN)

(73) Assignee: **Shenzhen Ulike Smart Electronics Co., Ltd.**, Shenzhen (CN)

(**) Term: **15 Years**

(21) Appl. No.: **29/974,756**

(22) Filed: **Nov. 25, 2024**

(30) **Foreign Application Priority Data**

Jun. 5, 2024 (CN) 202430343779.1

(51) **LOC (15) Cl.** **28-03**
(52) **U.S. Cl.**

USPC **D28/44.1**

(57) **CLAIM**

The ornamental design for a hair removal device, as shown and described.

DESCRIPTION

FIG. 1 is a front, right, and bottom perspective view of a hair removal device showing my design.

FIG. 2 is a rear, left, and top perspective view of FIG. 1.

FIG. 3 is a front elevation view of FIG. 1.

FIG. 4 is a rear elevation view of FIG. 1.

FIG. 5 is a left side elevation view of FIG. 1.

FIG. 6 is a right side elevation view of FIG. 1.

FIG. 7 is a top plan view of FIG. 1.

FIG. 8 is a bottom plan view of FIG. 1.

FIG. 9 is an exploded front perspective view of the hair removal device of FIG. 1, wherein the hair removal device is separated into two portions; and,

FIG. 10 is exploded rear perspective view of the hair removal device of FIG. 1, wherein the hair removal device is separated into two portions.

The broken lines in the drawings illustrate portions of the hair removal device that form no part of the claimed design.

1 Claim, 10 Drawing Sheets
